PHOTOGRAPHIC PRINT PROCESSING
APPARATUS

Adam N. Rittinger, Irondequoit, N.Y., assignor, by mesne assignments, to Itek Corporation, Lexington, Mass., a corporation of Delaware

Filed Apr. 6, 1960, Ser. No. 20,445
3 Claims. (Cl. 95—94)

This invention relates to photographic print processing apparatus and provides an apparatus for developing right-reading prints, such as black-on-white copies from a black-on-white original, in a single direct step. Photographic reproduction of documents and the like has heretofore commonly involved a negative intermediate print (white-on-black from a black-on-white original). The present invention provides apparatus for developing photographic paper of a positive, double coated type affording right-reading reproductions by a single direct step of developing and washing.

One object of the invention is to provide an apparatus of the above character, having a practical and efficient construction for developing photographic paper of the type described.

Another object is to supply such an apparatus adapted to operate efficiently at a relatively rapid rate of travel of the paper.

A further object is the provision of an apparatus of the above nature having a relatively simple and practical construction capable of operating efficiently and economically as regards the time, labor and materials involved.

To these and other ends the invention resides in certain improvements and combinations of parts, all as will be hereinafter more fully described, the novel features being pointed out in the claims at the end of the specification.

In the drawings:

FIG. 1 is a longitudinal sectional elevation, showing an apparatus embodying the present invention;

FIG. 2 is a transverse, sectional elevation of the apparatus on the line 2—2 in FIG. 3 as viewed from the right and showing portions of the spray washing section of the apparatus;

FIG. 3 is an enlarged, longitudinal, sectional elevation of the spray washing section of the apparatus shown in FIG. 1;

FIG. 4 is a transverse, sectional elevation on line 2—2 in FIG. 3, as viewed from the left; and

FIG. 5 is an enlarged detail of a portion of a pin bar employed in the apparatus.

The invention is embodied in the present instance in conjunction with a camera comprising a supply roll of photographic paper for feeding intermittently into the exposure plane and with means for cutting off an exposed portion of the paper and discharging it into the path of means for carrying it through the processing apparatus, all as disclosed, for example, in the patents to Caps et al. No. 1,824,259 and Greene et al. No. 1,894,092.

The present apparatus is specially designed for processing the known positive process paper of the type having a surface coated with two layers of emulsion. The upper or outer layer is a fast orthochromatic emulsion in a colloid made soluble by an alkaline developer and is sensitive to light and reacts normally to exposure to receive a negative image. During development, two reactions take place at the same time in the emulsion. One reaction causes the negative image of the photographed subject to appear in the upper layer. In the second reaction this negative image produces a positive image in the lower layer of the emulsion. The paper is then subjected to a thorough presoaking by water by which the soluble upper layer of the emulsion, no longer needed, is

2

softened to a condition in which it crumbles and can be stripped off in a pressure spray of water, leaving a positive, right-reading permanent photographic reproduction of the subject in the one step described, without the usual intermediate negative.

The present apparatus comprises (FIG. 1) a developing container section 10, a pressure spray washing container section 12 and a section, indicated generally at 14, comprising a plurality of containers for successive washings immersions of the print 15, as hereafter described in more detail. A supporting frame means 16 (FIG. 2) is mounted on the open upper ends of the containers to support the apparatus enclosed therein.

A photographic print such as described may be processed at a relatively rapid rate of travel through the developing fluid of the processing apparatus, provided it is continuously immersed in such fluid for a period of approximately sixty seconds. The present apparatus accordingly comprises a developing fluid container 10, of substantial depth as shown and means for carrying an exposed print downwardly and upwardly in the fluid a plurality of times, while continuously immersed below the surface of the fluid. To this end the supporting frame means on the containers carries a series of longitudinally spaced, transversely extending shafts as 18 (FIG. 2) each journaled at its ends in the supporting frame means on opposite sides of the containers. These shafts are rotated by means hereafter described and have rollers 20 fixed on their central portions for contact with the prints as

they are carried through the apparatus by print carrying means of the known continuous sprocket chain and pin bar type disclosed in said patents and hereafter described. The series of shafts 18 comprise similar parts similarly mounted and driven, so that a description of one will apply to all.

The supporting frame means at each side of the container 10 carries a pair of transversely aligned, substantially Z-shaped brackets 22 (FIG. 4), each secured by a bolt 24 on a boss 26 on the frame means, substantially as described in said Patent No. 1,824,259. Each bracket 22 has its lower inner side formed with a rectangular notch below the inwardly extending top of the bracket and the top of the bracket carries an adjustable tensioning bolt 28, these parts providing for the support and adjustment of the separator frames as hereafter more fully described. The separator frames 30, of which there are two in container 10, are alike, each comprising a pair of side posts, as 32, connected by a transversely extending partition 34. The upper ends of the side posts are received in the respective notches in the brackets 22, bearing at their upper ends against the tension adjusting bolts 28. The lower ends of the side posts of each separator frame are provided with bearings supporting a transversely extending shaft 36 having rotary elements in the form of chain guiding disks 38 adjacent its opposite ends and a print receiving roller 40 at its central portion. The lower end of each side post has a circular flange 42 to insure minimum spacing between the separator frames and between such frames and the sides of the container.

The supporting frame means, intermediate the separator frames in the developing container 10, supports a cross shaft 44 carrying adjacent each end a hanger strap 46 depending below the fluid surface in the container. The lower ends of the straps are formed with bearings supporting a cross shaft 47 carrying a roller 48 for receiving the prints carried by the sprocket chains and the latter are carried by guiding disks 50 similar to the disks 38 of the separator frames. The endless sprocket chain 52 at each side of the apparatus passes around a rotary element or driving sprocket wheel 54 on the supporting frame (FIG. 1) downwardly adjacent the bottom of the con-

tainer, around the guiding disk 38 of the first separator frame and upwardly around the guiding disk on the shaft 47 of the intermediate roller 48, below the surface of the container fluid. Each chain then passes downwardly around the guiding disk on the shaft at the lower end of the second frame and thence upwardly out of the container around the rotary elements or sprocket wheels on the transverse shafts journaled in the supporting frame means.

By providing a developing container of substantial depth and a plurality of upward and downward passes through the fluid, the prints may be moved through the developing fluid for a sufficient period, as sixty seconds, to allow for a satisfactory rate of travel of the prints. Furthermore, by maintaining the prints submerged in the fluid during such travel, a continuous treatment of maximum intensity is preserved without interference by air bubbles which would otherwise be trapped in the print if carried above the liquid surface during such treatment.

From the developing container 10, the chains carry the prints over further rollers, as 56, on shafts journaled in the supporting frame means and down into the spray washing container 12. Container 12 is separated by a partition 58 into a first compartment 60 and a second compartment 62 communicating with each other adjacent the bottom of the container. Partition 58 is carried by a separator frame comprising side posts 64 adjustably mounted at their upper ends by brackets as described above in connection with the separator frames of the developing container. The lower ends of the opposite side posts are provided with bearings for a shaft 36 (FIGS. 3 and 4) and print receiving roller 40, as described above in connection with the separator frames of the developing container. Such shaft is likewise provided with the chain guiding disks 38, as described above. The lower end of each side post of separator frame 64 is enlarged as at 66 and retained between the container side and a spaced angle iron 68 (FIG. 4) fixed on the side of the container. The separator frames of each container are held up against the tension adjusting bolts 28 of the brackets 22 by the carrier chains 52 which are tensioned by adjusting the bolts.

The second compartment 62 of the spray washing container has mounted therein a wash plate or board 70 (FIGS. 1-3) supported by stud bolts 72 passed therethrough and threadedly engaged in the flanges of angle bars 74 fixed to the sides of the container. The wash board carries adjusting stop screws 76 for accurately determining the position of the wash board as drawn against the stop screws 76 by the studs 72. It will be seen that the wash board extends from adjacent the bottom of the container compartment upwardly and at a longitudinal inclination away from partition 58 and in the direction of travel of the print carrying chains. The chains pass around rotary elements or sprockets 78 of the transverse shafts on the supporting frame means, down into the first compartment, around the guide disks 38 adjacent the bottom of the container and thence upwardly, along the under side of the wash board 70 and in spaced relation therewith as controlled by the screws 76 (FIG. 3). The chains then pass upwardly out of the second compartment around the rotary elements or sprockets 80 on the supporting frame means and down into the series of immersion containers hereafter described.

Extending laterally across the compartment 62 is a pipe 82 connected through one side of the container (FIG. 2) with a source of water under pressure. Pipe 82 carries a plurality of spray nozzles 84 spaced therealong and positioned to direct forceful sprays of water toward the wash board and the emulsion side of a print as it is carried upwardly in spaced relation with the wash board, with the result that the print is thoroughly presoaked from both sides with water as it rises through the compartment. By the time the print reaches proximity with the spray nozzles, the upper soluble emulsion layer has

acquired a crumbling consistency so that the force of the sprays strips such layer from the print, leaving only the under layer with the permanent image carried thereby intact on its paper base.

Compartment 62 of the container is provided at its bottom with a discharge outlet 86 by means of which the spray water and stripped emulsion are continuously carried away so as to prevent accumulation in the container and contamination of the print.

The developed print, stripped cleanly down to its permanent image emulsion, then passes into the series of immersion containers 14, each having therein a separator frame depending from the frame supporting means on the containers as described above in connection with containers 10 and 12, the print being carried downwardly and upwardly in each of the containers to thoroughly wash the same and the carrying chain means, as disclosed in said patents. From these containers the print is carried to such further disposition as may be desired, the endless carrying chains returning, by any known and suitable means not shown, to the point of engagement of the prints discharged from the camera.

The means for driving the rotary elements or transverse shafts on the supporting frame means preferably comprises a worm wheel 88 fixed on one end of each shaft 18 (FIG. 2) meshing with a worm 89 on a shaft 90 driven by any suitable means as described in said patents.

The print engaging and carrying means is preferably of the known pin bar type in which the chains at the opposite sides of the apparatus carry the ends of cross bars 92 (FIG. 5) having pins 94 projecting forwardly therefrom so as to pierce and engage the prints delivered from the camera, as disclosed in said patents.

The side wall of the first compartment 60 of the spray washing container 12 is fitted with a series of laterally spaced ribs 96 extending downwardly from the top of the side wall and across the bottom of the container for the purpose of preventing contact of the print with the container walls.

It is apparent from the above description that the apparatus is effectively adapted to receive and subject the exposed prints to developing treatment for a satisfactory period, say sixty seconds, while moving at a relatively rapid processing speed. This is accomplished by moving the paper, while wholly submerged in the developing fluid, through a path of sufficient length, obtained by multiple passes through the fluid or by a container of sufficient size. After such development, the print is carried through the atmosphere to the bottom of the spray washing container and thence upwardly through a space in which it is thoroughly presoaked to soften the outer emulsion. Then the emulsion side of the print encounters at close range the pressure spray which strips off the softened emulsion for discharge at the bottom of the container. The print is then subjected to repeated immersion washing for thorough cleansing, after which it may be dried in the usual manner, yielding a positive, right-reading, high quality permanent photocopy print of the object photographed in a single direct step, without resort to negative intermediates, and thus effecting substantial savings in time, labor and materials.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. In an apparatus for processing positive process paper, said paper comprising an emulsion having an outer layer that is sensitive to light, reactive normally to exposure to receive a negative image, and is in colloid form made

soluble by an alkaline developer to cause said negative image to appear in said outer layer and a lower layer in which said negative image produces a positive image, said apparatus comprising:

a first container for fluid to develop an exposed portion 5
of said paper;

a second container for fluid to spray wash a developed portion of said paper;

means for conveying said exposed portion of said paper 10
through said first container and to said second container;

a separator frame depending into said second container and having thereon a partition dividing said second container into a first compartment and second compartment communicating with each other adjacent 15
the bottom of said second container;

spaced rotary elements at the lower end of said frame 20
between said first and second compartments;

a washboard mounted in said second compartment and inclined upwardly therein and away from said partition;

spaced endless flexible carrying members passing downwardly in said first compartment and around said rotary elements and upwardly in said second compartment adjacent and spaced below said inclined 25
washboard and engaging and carrying said exposed portion through said first and second compartments in succession;

fluid pressure spray means in said second compartment adjacent the upper side of said washboard for spraying both sides of said exposed portion carried by said members to remove spent emulsion therefrom; and means for draining the bottom of said second container 30
to discharge the spent fluid and emulsion.

2. In an apparatus for processing positive process paper, 35
said paper comprising an emulsion having an outer layer that is sensitive to light, reactive normally to exposure to receive a negative image and is in colloid form made soluble by an alkaline developer to cause said negative image to appear in said outer layer and a lower layer in 40
which said negative image produces a positive image, said apparatus comprising:

a first container for fluid to develop an exposed portion 45
of said paper;

a second container for fluid to spray wash a developed portion of said paper;

means for conveying said exposed portion through said first container and to said second container;

supporting frame means at the upper end of said second 50
container;

a separator frame depending from said supporting frame means into said second container and having thereon a partition dividing said second container into a first compartment and a second compartment communicating with each other adjacent the bottom of said second container;

spaced rotary elements on said supporting frame means 55
and on the lower end of said separator frame;

a washboard mounted in said second compartment and inclined upwardly and longitudinally of said second container;

spaced endless carrying sprocket chain passing around 60
said spaced rotary elements on said supporting frame means, downwardly in said first compartment and around said rotary elements on said separator frame and upwardly in said second compartment adjacent and spaced longitudinally from said inclined washboard for engaging and carrying said exposed portion through said first and second compartments in succession;

a plurality of spray nozzles in said second compartment adjacent the top of said washboard on the side thereof opposite said partition for spraying both sides 65
70

of said exposed portion carried by said chain in said second compartment to remove softened emulsion therefrom; and

means for continuously draining the bottom of said washing container to discharge spent fluid and emulsion.

3. In an apparatus for processing positive process paper, said paper comprising an emulsion having an outer layer that is sensitive to light, reactive normally to exposure to receive a negative image, and is in colloid form made soluble by an alkaline developer to cause said negative image to appear in said outer layer and a lower layer in which said negative image produces a positive image, said apparatus comprising:

a first container for fluid to develop an exposed portion 25
of said paper;

a second container juxtaposed with said first container for fluid to spray wash a developed portion of said paper;

supporting frame means on the upper ends of said first and said second container;

a plurality of spaced separator frames depending into said first container from said supporting frame means; spaced rotary elements on said supporting frame means and on the lower ends of said plurality of separator frames;

spaced rotary elements carried by said supporting frame means intermediate said plurality of separator frames in said first container adjacent and below the fluid surface therein;

a separator frame depending into said second container and having thereon a partition dividing said second container into a first compartment and a second compartment, said first compartment communicating with said second compartment adjacent the bottom of said second container;

spaced rotary elements at the lower end of said separator frame between said first compartment and said second compartment;

a washboard mounted in said second compartment and inclined upwardly therein and away from said partition;

spaced endless flexible paper carrying members passing around said rotary elements on said supporting frame means and on the lower ends of said plurality of separator frames in said first container and said separator frame in said second container, said carrying members passing said exposed portion through said first container continuously below the fluid surface therein and downwardly in said first compartment and upwardly in said second compartment of said second container adjacent and spaced below said washboard;

fluid pressure spray means in said second compartment adjacent the upper side of said washboard for spraying both sides of said exposed portion carried by said carrying members to remove spent emulsion therefrom; and

means for draining the bottom of said second container to discharge the spent fluid and emulsion.
